UNITED STATES PATENT OFFICE

ERNST L. RUBY, OF JENKINTOWN, PENNSYLVANIA

SWITCH HEATER

Application filed March 28, 1932. Serial No. 601,489.

This invention relates to improvements in gas burning switch heaters for the protection of switches and other parts of railroad structures against the interference with the proper functioning thereof by the encroachment of snow and ice during cold and stormy weather.

An object of the invention is to provide a novel and advantageous construction wherein the heating flame of burning gas is well protected against being accidentally extinguished by the wind and by air currents and blasts created by rapidly moving trains passing over the heater. Another object of the invention is to provide a heater construction which, while providing ample heat for the purpose intended, will protect the wooden cross ties of the railroad from being burned or scorched by the flame of burning gas during the operation of the heater. Another object is to provide a construction and arrangement of parts wherein natural gas, manufactured gas or a combination of them may be efficiently burned therein under the adverse conditions to which switch heaters are subjected. A further object is to provide a novel means for connecting the heater to a railroad rail and for holding it in proper working position with relation thereto.

The invention resides in the elements and the combinations of them hereinafter described and claimed.

In the accompanying drawings, illustrating the invention,

Figure 1 is a transverse section, partly broken away, of a switch portion of a railroad structure showing my improved switch heater applied thereto.

Figure 2 is a side view, partly broken away, of the parts shown in Fig. 1.

Figure 3 is a vertical section of the heater, on line 3-3 of Fig. 2.

Figure 4 is a vertical section of the heater, on line 4-4 of Fig. 1.

Figure 5 is a top view of one of the burner boxes of the heater.

Figure 6 is a bottom view of the burner box shown in Fig. 5.

Figure 7 is a transverse section of a rail-

road switch showing the parts thereof illustrated at the right hand side of Fig. 1, and showing a modified form of my improved heater, in section.

Figure 8 is a bottom view of the parts shown in Fig. 7.

Referring to Figs. 1 to 6, inclusive, of the drawings, 2 designates the stationary track rails, 5 the movable switch rails, 6 the tie plates supporting the rails, and 7 the cross ties supporting the tie plates.

My improved switch heater is arranged beneath the rails 2 and 5 and within the space between two adjacent cross ties 7.

A burner box 8 is provided for each track rail 2 and its adjacent switch rail 5 at each side of the switch, and the boxes 8 are connected and supported by a fuel or gas pipe 9 which extends transversely beneath the rails and parallel to the cross ties.

The fuel pipe is made in connected sections, one of which is a centrally arranged insulated coupling 10 to electrically insulate from each other the parts on the respective end portions of the pipe which are in contact with the rails 2.

One end portion of the fuel pipe 9 is provided with a collar 11, having a jaw 12 adapted to extend over and engage the outer flange of the base 13 of one track rail 2, and the other end portion of the pipe 9 has a collar 14 slidably thereon and provided with a jaw 15 adapted to extend over and engage the outer flange of the base 13 of the other track rail 2. The collar 11 may be fixed to the pipe 9, to prevent outward movement of the collar on the pipe, or such movement may be prevented by the adjacent head 16 which is screwed on to the pipe to

close the end thereof. The pipe 9 extends outwardly from the collar 14 and may be connected in any desired manner to a suitable source of fuel supply. The outwardly extending end of the pipe 9 carries a spring 17 adapted to have its outer end engaged with a collar on the pipe. The inner end of this spring 17 engages the collar 14 and urges it toward the collar 11 and thereby causes the jaws 12 and 15 to grip the rail

85

base flanges 13 and hold the entire heating device firmly in place.

The burner boxes 8 are alike in construction and therefore I shall describe but one of them.

The box 8 has an open top and an open bottom and it comprises side walls 19 which extend parallel to the rails 2 and 5, and end walls 20 which extend transversely of the 10 rails.

Within the box 8 are two parallel walls 21 which extend between and are connected to the end walls 20. These walls 21 extend parallel to the side walls 19 in spaced relation thereto, the upper ends of the walls 21 being below the upper ends of the end walls 20, and the lower ends of the walls 21 being above the lower ends of the end walls 20 and the side walls 19, as illustrated in the 20 drawings.

The upper and lower ends of the inner walls 21 are connected by upper and lower horizontal walls 22 and 23, respectively, which have their ends spaced from the end walls 20 of the box. The lower wall 23 is provided with a centrally arranged air passage 24 which extends vertically therethrough.

The side walls 19 have their top surfaces 30 below the upper ends of the end walls 20 to provide passages leading from the interior of the box and over the side walls 19 and between the end walls 20.

Each box 8 is supported by a section 25 of the fuel pipe 9, and the pipe section 25 extends through the side walls 19 and the vertical inner walls 21 of the box and between the upper and lower horizontal walls 22 and 23, respectively, and it is provided with fuel 40 discharging openings 26 on the respective sides thereof, as shown in Figs. 3 and 4. These fuel discharging openings 26 are located between the inner walls 21 of the box and they are directed toward the end walls 45 20 thereof, the axis of the openings 26 intersecting the end walls 20 well below the upper ends thereof.

One end of the pipe section 25 extends outwardly from one side of the box 8 and 50 is threaded for the reception of a coupling member 27 by means of which the section 25 is connected to the adjacent section of the pipe 9. The other end of the pipe section 25 extends outwardly from the other side of the box 8 and has a head 28 formed thereon and provided with a flat upper surface 55 adapted to engage the flat bottom surface of a lug 29 formed on and projecting outwardly from the adjacent side wall 19 of the box.

The space between the coupling member 27 and the head 28 is substantially equal to the space between the outer surfaces of the side walls 19 of the box, and thus the member 27 and head 28 serve to hold the box in

place against displacement thereof longitudinally of the pipe; and the engagement of the flat top of the head 28 with the lug 29 serves to prevent relative turning of the box and the pipe section, on the axis of the 70 latter.

The upper ends of the end walls 20 of the box 8 are flush with the bottom surface of the adjacent track rail 2 and the box is positioned below the rail 2 so that the base 75 thereof will extend part way over the box at all times, and so that the base of the adjacent switch rail 5 will occupy a position over the box when the switch rail is closed against the track rail, as shown at 80 the left hand side of Fig. 1, and so that the box 8 will be under the space between the track rail 2 and the switch rail 5, when the switch rail is in the open position, spaced from the track rail, as shown at the right 85 hand side of Fig. 1.

When the heater is in service, the pipe 9 is connected to a suitable source of gas supply under pressure. The gas discharged from the openings 26 is ignited and the burning flames projected from the openings, strike against the opposing end walls 20 of the burner box and then extend upwardly through passages 30 provided between the end walls 20 and the ends of the upper horizontal wall 22, and they may then extend outwardly over some or all of the top surfaces of the vertical walls 19, 20 and 21 of the box.

When the switch rail 5 is in the closed 100 position, shown at the left hand side of Fig. 1, the flames rising through the passages 30 at the respective ends of the box 8, impinge against the bottom surfaces of the rails 2 and 5 and heat the same, and the flames and air currents supporting combustion may pass out between the tops of the end walls 20 and the bottom of the switch rail and also out through the passages provided between the end walls 20 and over the 105 side walls 19.

When the switch rail 5 is in the open position, shown at the right hand side of Fig. 1, the major portions of the flames rising through the passages 30 will rise through the space between the track rail 2 and switch rail 5 and some parts thereof will strike the bottom of the track rail and pass out through the spaces between the track rail and the top of the side wall 19 beneath the same on the respective sides of the lug 29.

In any position of the switch rail 5 with respect to the track rail 2, sufficient air enters the open bottom of the box 8 and passes up through the same to support combustion for the production of hot flames, some of the upwardly moving air passing through the passage 24 in the lower horizontal wall 23 to the space between the in- 125

ner vertical walls in the region of the gas discharging openings 26.

The arrangement of the fuel discharging openings 26 with relation to the end walls 20 of the burner box 8 enables me to provide the desired hot flames for effectively preventing the detrimental accumulation of ice and snow between and about the rails of the switch, and, at the same time, prevents the 10 flames from reaching and burning or scorching or detrimentally heating the wooden cross ties 7.

I have discovered that a burner box provided with walls constructed and arranged 15 relative to each other and to the fuel discharging openings 26 of the gas pipe, not only produces the desired hot flames with the use of either natural gas or manufactured gas or combination of the two, but 20 also provides a construction which successfully resists the accidental extinguishment of the flames by the wind and other air currents to a greater extent than any gas burning switch heater in use prior to my invention.

In practice, a number of pairs of burner boxes 8 like that shown in Fig. 1, are employed at a switch in the successive spaces between adjacent cross ties, in order that 30 the entire switch may be properly heated for the purpose intended, and the fuel pipes of the several pairs of boxes may be arranged and connected to be supplied with gas from a simple lead in pipe in a manner 35 similar to the connections of the fuel pipes shown and described in Letters Patent No. 1,273,291, dated July 23, 1918.

In the modification of the invention shown in Figs. 7 and 8 a fuel box 31 is provided 40 and constructed just like the boxes 8 shown in Figs. 1 to 6, inclusive, excepting that the end walls of the box 31 are provided with upwardly projecting lugs 32 and the side walls 33 of the box 31 beneath the track rail 45 2 has its top surface flush with the top surfaces of the end walls 20 and the side wall 33 is provided with an outwardly extending arm 34.

The upper surface of the arm 34 is fitted 50 against the bottom of the rail 2 and the outer end of the arm is provided with an upwardly projecting lug 35. The lugs 32 and 35 are located adjacent to the respective sides of the base of the rail 2 for the purpose of engaging the same and preventing 55 displacement of the box 31 and its arm 34 transversely of the rail.

The rail 2 and the arm 34 and box 31 are held firmly together by means of a spring 60 clip 36 which embraces one side of the rail base 13 and the outer end portion of the arm 34 and clamps them together. The clip 36 is provided with an arm 37 which engages the top of the rail base 13, and an arm 38 65 which engages the bottom of the arm 34,

and the free end of the arm 38 is provided with an upwardly projecting lug 39 which enters a slot 40 in the arm 34 and is adapted to engage one side wall of the slot and hold the clip in place.

The fuel pipe section 41 of the box 31 is like the pipe section 25 of the box 8, shown in Fig. 1 and it forms a continuation of an outwardly extending pipe 42 which may be connected to a suitable source of gas supply. The end of the pipe section 41 opposite to the head 43 thereon is provided with a head or cap 44 which closes the end of the pipe section.

All parts of each burner box shown in Figs. 1 to 6, inclusive, are formed of a single casting supported by the fuel pipe 9, which extends through the same and which is supported by the rails 2; and all parts of the box 31 and the arm 34 extending therefrom shown in Figs. 7 and 8 are formed of a single casting which is supported by the rail 2 and which supports its fuel pipe sections 41 and 42.

I claim as my invention,

1. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, and a substantially horizontal wall supported between said end walls in spaced relation thereto and below the upper ends thereof; and a fuel pipe extending through the side walls of the box and having fuel discharging openings beneath said horizontal wall.

2. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, said side walls having top surfaces below the upper ends of said end walls for the escape of flame between the end walls and over the side walls, and a substantially horizontal wall supported between said end walls in spaced relation thereto and below the upper ends thereof; and a fuel pipe extending through the side walls of the box and having fuel discharging openings beneath said horizontal wall.

3. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, and a substantially horizontal wall supported between said end

- walls below the upper ends thereof and being spaced from said end walls and also from said side walls; and a fuel pipe extending through the side walls of the box and 5 having fuel discharging openings beneath said horizontal wall.
4. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, said side walls having 10 top surfaces below the upper ends of said end walls for the escape of flame between the end walls and over the side walls, and a substantially horizontal wall supported between said end walls below the upper ends thereof and being spaced from said end walls and also from said side walls; and a fuel pipe extending through the side walls of the box and having fuel discharging openings beneath said horizontal wall.
5. In a gas burning switch heater, a burner box adapted to be supported below a railroad rail in close proximity to the bottom thereof and having an open top and an open bottom and comprising side walls adapted to extend substantially parallel to the rail, and end walls adapted to extend transversely of the rail, said side walls having top surfaces below the upper ends of said end walls for the escape of flame between the end walls and over the side walls; and a fuel pipe extending through the side walls of the box and having fuel discharging openings directed toward said end walls.
6. In a gas burning switch heater a burner box adapted to be supported below a railroad rail in close proximity to the bottom thereof and having an open top and an open bottom and comprising side walls adapted to extend substantially parallel to the rail, end walls adapted to extend transversely of the rail, vertical inner walls spaced from the side walls and connecting the end walls, a substantially horizontal wall spaced from said end walls and connecting the upper portions of said inner walls; and a fuel pipe extending through said side walls and said inner walls and having fuel discharging openings therein between said inner walls and beneath said horizontal wall.
7. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, said side walls having top surfaces below the upper ends of said end walls for the escape of flame between the end walls and over the side walls, vertical inner walls 60 below the upper ends of said end walls for the escape of flame between the end walls and over the side walls, a substantially horizontal wall spaced from said end walls and connecting the upper portions of said inner walls, a substantially horizontal wall spaced below the first named horizontal wall and spaced from said end walls and connecting the lower portions of said inner walls and having an air passage extending vertically therethrough; and a fuel pipe extending through said side walls and said inner walls and between said horizontal walls and having fuel discharging openings therein between said inner walls and between said horizontal walls.
8. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, vertical inner walls spaced from the side walls and connecting the end walls, a substantially horizontal wall spaced from said end walls and connecting the upper portions of said inner walls, a substantially horizontal wall spaced below the first named horizontal wall and spaced from said end walls and connecting the lower portions of said inner walls and having an air passage extending vertically therethrough; and a fuel pipe extending through said side walls and said inner walls and between said horizontal walls and having fuel discharging openings therein between said inner walls and between said horizontal walls.
9. In a gas burning switch heater, a burner box adapted to be supported below a railroad rail in close proximity to the bottom thereof and having an open top and an open bottom and comprising side walls adapted to extend substantially parallel to the rail, end walls adapted to extend transversely of the rail, said side walls having top surfaces below the upper ends of said end walls for the escape of flame between the end walls and over the side walls, vertical inner walls spaced from the side walls and connecting the end walls, a substantially horizontal wall connecting the upper portions of said inner walls in spaced relation to said end walls and below the upper ends thereof; a substantially horizontal wall spaced from said end walls and connecting the lower portions of said inner walls and having an air passage extending vertically therethrough; and a fuel pipe extending through said side walls and said inner walls and between said horizontal walls and having fuel discharging openings therein between said inner walls and between said horizontal walls.
10. In a gas burning switch heater, a burner box adapted to be supported below a railroad rail in close proximity to the bottom thereof and having an open top and an open bottom and comprising side walls adapted to

- to extend substantially parallel to the rail, end walls adapted to extend transversely of the rail, and an arm extending outwardly from one of said side walls and having a top 5 surface adapted to engage the bottom of the rail, said box and said arm having upwardly projecting lugs adapted to engage the respective sides of the base of the rail; a fuel pipe extending through said side walls and 10 having fuel discharging openings within the box, and a spring clip adapted to embrace said arm and the base of the rail.
11. A switch heater burner box adapted to be supported below a railroad rail in close 15 proximity to the bottom thereof and being formed of a casting comprising side walls adapted to extend substantially parallel to the rail, end walls adapted to extend transversely of the rail, an arm extending outwardly from one of said side walls and having a top surface adapted to engage the bottom of the rail, and spaced lugs projecting above the plane of said surface and adapted to engage the respective sides of the 20 base of the rail.
12. A switch heater burner box adapted to be supported below a railroad rail in close proximity to the bottom thereof and being formed of a casting comprising side 25 walls adapted to extend substantially parallel to the rail, end walls adapted to extend transversely of the rail, an arm extending outwardly from one of said side walls and having a top surface adapted to engage the bottom of the rail, the side wall remote from the side 30 wall from which the arm extends having a top surface below the plane of the top surface of the arm for the passage of flame thereover, and spaced lugs projecting above the plane of said surface and adapted to engage the respective sides of the base of the rail.
13. A switch heater burner box adapted to be supported below a railroad rail in close 35 proximity to the bottom thereof and being formed of a casting comprising side walls adapted to extend substantially parallel to the rail, end walls adapted to extend transversely of the rail, an arm extending outwardly from one of said side walls and having a top surface adapted to engage the bottom of the rail, and spaced lugs projecting above the plane of said surface and adapted to engage the respective sides of the base of the rail.
14. A switch heater burner box adapted to be supported below a railroad rail in close proximity to the bottom thereof and being 40 formed of a casting comprising side walls adapted to extend substantially parallel to the rail, end walls adapted to extend transversely of the rail, a substantially horizontal wall supported between said end walls in 45 spaced relation thereto and below the upper 50 ends thereof, an arm extending outwardly from one of said side walls and having a top surface adapted to engage the bottom of the rail, and spaced lugs projecting above the plane of said surface and adapted to engage the respective sides of the base of the rail.
15. A switch heater burner box adapted to be supported below a railroad rail in close proximity to the bottom thereof and being 55 formed of a casting comprising side walls adapted to extend substantially parallel to the rail, end walls adapted to extend transversely of the rail, a substantially horizontal wall supported between said end walls in 60 spaced relation thereto and below the upper 65 ends thereof, an arm extending outwardly from one of said side walls and having a top surface adapted to engage the bottom of the rail, the side wall remote from the side wall from which the arm extends having a top surface below the plane of the top surface of the arm for the passage of flame thereover, and spaced lugs projecting above the plane of said surface and adapted to engage the respective sides of the base of the rail.

In testimony whereof I affix my signature.

ERNST L. RUBY.
